UNITED STATES PATENT OFFICE.

WILLIAM F. COOPER, OF NORWALK, OHIO, ASSIGNOR OF ONE-HALF TO THE
A. B. CHASE CO., OF NORWALK, OHIO, A CORPORATION OF OHIO.

TRACKER-BOX FOR MECHANICAL MUSICAL INSTRUMENTS.

No. 856,769.

Specification of Letters Patent.

Patented June 11, 1907.

Application filed June 14, 1905. Renewed April 30, 1907. Serial No. 371,055.

To all whom it may concern:

Be it known that I, WILLIAM F. COOPER, a citizen of the United States of America, residing at Norwalk, in the county of Huron 5 and State of Ohio, have invented certain new and useful Improvements in Tracker-Boxes for Mechanical Musical Instruments, of which the following is a specification, reference being had therein to the accompanying drawing.

This invention has relation to tracker boxes for mechanical musical instruments, and has for its object the provision of a tracker box of novel form and construction 15 adapted to be applied to a musical instrument, such as a piano, or other similar keyed instrument, provided with means for mechanically playing the same.

The tracker box of a mechanical musical instrument, it is to be understood, is a box or casing which contains the roll of perforated paper, and the feeding roll upon which the perforated paper is wound over the tracker bar during the operation of playing the instrument, and in carrying my invention into effect, I pivotally connect the tracker box to a suitable support mounted on or in the instrument to be played, so that when the tracker box is in the position which it occupies when the piano is being played mechanically, it will stand in front of the keys of the instrument, but when the instrument is to be played in the ordinary manner, the tracker box will be swung downwardly on its pivotal supports so as to hang beneath the key-board, at which last named position it will offer no obstacle or obstruction to the playing of the instrument in the ordinary manner, and will, in fact, be substantially concealed by the key-board and out of sight so as not to detract from the appearance of the piano or instrument to which it is attached.

A further object of my invention is to provide simple and novel means for supporting the tracker box in its active, that is, its elevated position, in front of the key-board, and to support the same when in its inactive position under the keyboard.

A still further object of my invention is to provide novel means for effecting a proper and substantially air tight connection between the ducts which lead from the tracker bar to the tracker box and which are, of

course, movable with the tracker box, during the operation of raising or lowering the 55 tracker box, and the stationary ducts which lead from the tracker box support to the pneumatic operating mechanism of the instrument.

With the above, and with other objects 60 which will be hereinafter developed, in view, my invention consists in the novel construction, combination and arrangement of parts hereinafter described and particularly set forth in the claims.

In the accompanying drawing, in which I have illustrated my improvement, and in the several figures of which like numerals designate corresponding parts: Figure 1, is a perspective view of a mechanical musical instrument of the upright piano type, showing my improved tracker box in its inactive position, that is, when it is swung down beneath the keyboard of the instrument. Fig. 2, is a similar view, showing the tracker box in its 70 active or elevated position. Fig. 3, is a front elevation showing the tracker box on an enlarged scale, and with a portion of the exterior covering thereof removed so as to expose the internal operating parts. Fig. 4 80 is a top plan view on the same scale as Fig. 3, and showing in plan view the pivotal connecting devices and the spring catches by which the tracker box is sustained in its elevated position. Fig. 5 is an end elevation of 85 the tracker box and a portion of the support therefor, the tracker box being shown in its elevated position in full lines and in its lowered position in dotted lines. Fig. 6 is a vertical transverse sectional view on the line 90 x—x of Fig. 4. Fig. 7 is a fragmentary sectional view on line x—x of Fig. 6. Fig. 8 is a fragmentary detail view of a modification. Fig. 9 is a fragmentary vertical sectional view on the line y—y of Fig. 6. Fig. 10 is a 95 plan view of one of the jointing bars of the tracker box.

The tracker box proper is connected to and sustained in either of its positions by means of two bars designated 1, 1, which are attached at their inner ends to any suitable portion of the instrument casing or any suitable portion of the mechanical playing apparatus contained within the casing and these bars extend beneath the bottom of the key-board of the instrument, and to the outer end

of each of the bars 1, is securely bolted or otherwise attached, an L-shaped casting 2, these castings being formed with pierced ears 3, through which pass thumb screws 4, that serve to attach the castings 2, firmly to the bottom of the key-board of the instrument.

The castings 2, 2 are of channeled formation in cross section, the channels being on 10 the inner sides of the castings and serving to receive the chamfered ends of a cross bar 5, the connection between the ends of the cross bar and the casting being shown at 6 in Fig. 7 of the drawing.

15 Screws 7, extend through the outer arms of the L-shaped castings 2, and screw into the cross bar 5, and this cross bar forms the stationary terminal of the tubes or ducts which lead to the pneumatic action of the instrument, and it will, for the sake of brevity and clearness in the description, be hereinafter termed the outer jointing bar.

20 A strong curved spring 8, is attached by a screw 9, to each of the castings 2, and the tension of this spring is regulated by a screw, 10, that passes through the inner end of the spring and screws into the casting 2. The outer end of each of the springs 8 terminates in a triangular head or block 11, that engages 25 a similarly shaped latch block 12, that is attached by screws 13, 13, to the bracket 14 that supports the tracker box.

25 The brackets 14, 14, of which there are two; one at each end of the tracker box, or adjacent each end, are of peculiar form, but may be said to be, generally speaking, of L-shape, one leg of each bracket being, when the tracker box is in its elevated position, horizontally aligned with the bottom of the key-board of the instrument, and the other leg of the bracket being at the same position of parts, in substantially a vertical position. The inner ends of the horizontal legs of the brackets spread somewhat so as to form a 40 broad bearing surface as illustrated in Fig. 4 and a portion of each bracket extends under each of the castings 2, while another portion thereof extends outwardly and provides a seat for the latch block 12. The extreme 45 inner ends of the brackets 14, are flattened and pierced for the passage of bolts, by means of which the brackets are pivotally attached to downwardly extending lugs 16, formed on the castings 2.

50 A cross bar 17, extends beneath the outer jointing bar 5, and is suitably connected to each of the brackets 14, and this bar, which will be hereinafter called the lower jointing bar, is formed with a series of ports 18, that 55 are disposed side by side and in a horizontal plane and which have upwardly extending branches 19, that are disposed in staggered relation and that meet and register with vertical branches 20, of horizontally disposed ports 21 in the outer jointing bar 5. Curved

tubes 22 of lead, rubber, other suitable material connect the movable jointing bar 17 with the tracker 23, that is mounted in the tracker box and similar tubes 22' connect the outer jointing bar 5, with an inner jointing bar 70 (not shown) that is in turn connected by suitable tubes or ducts with the pneumatics of the instrument.

The exterior configuration of the tracker box may be varied to suit the taste of the manufacturer or to conform to the particular style or type of the instrument to which the tracker box is to be applied, but I have shown this exterior casing of such shape as will conform as closely as possible to the assembled mechanism that is to be contained therein.

75 The tracker box framing is composed of the ends or heads 24, 25, and the intermediate section or partition 26, which conforms 80 in shape to the head 25 and is arranged adjacent thereto, as shown in Fig. 3; sufficient space, however being left between the partition 26 and the head 25 for the reception of 85 certain operating mechanism that will be 90 presently described.

95 An exterior panel 27, of wood or metal, is provided and this panel, together with an exterior paneling 28 of celluloid or other suitable transparent material constitute the external covering or casing of the tracker box, and internal panels 29, curved to correspond 100 to the contour of the brackets 14, are also provided, these latter panels serving to segregate the paper roll and paper feeding roll 100 from the ducts or tubes 22.

The paper roll is preferably located near the top of the tracker box and is designated 105 30, and this roll is provided with a stub shaft 31, at each end, the stub shaft at one end socketing in a bearing 32, carried on the inner end of a spring 33, that is mounted on the inner side of the head 24, while the stub shaft at the other end seats in a clutch shaft 34 journalled in a bearing 34', that is mounted 110 in the partition 26.

115 The head 24, and the partition 26 are connected respectively to the brackets 14, 14, and the brackets therefore constitute the connection between the tracker box and the stationary supporting means carried by the piano, and including the bars 1, 1, and castings 2, 2, and as the brackets are preferably arranged on the inside of the head 24 and the inside of the partition 26, the spring 33; and the bearing 34, can, if desired, be attached 120 to the brackets instead of the head 24, and the partition 26, as herein before described.

125 The take up or feed roll of the tracker box, designated 35, is preferably disposed below and in substantially vertical alignment with the paper roll 30, and this roll, 35, is provided with a stub shaft 36, at each end, the said stub shafts, turning respectively in a bearing 37, carried by a spring 38, and a bear- 130

ing 39, carried on the end of a screw 40, the spring 38 being attached to the head 24 and the screw 40 working in a screw threaded hole in the partition 26.

5 The stub shaft adjacent to the screw 40 carries a gear wheel 41 and this gear wheel meshes, during the normal operation of the tracker box mechanism, with a pinion 42, that is mounted on the inner end of a longitudinally movable shaft 43, that turns and slides in bearings in the partition 26 and the head 25. The shaft 43 has rigidly mounted upon it, a small sprocket wheel 44 that carries on its inner side a clutch member 45, which, at a certain position of the sprocket wheel 44, meshes with a clutch member 46, carried by a larger sprocket wheel 47 that is loosely mounted on a shaft 43.

20 A chain 48 passes around the small sprocket wheel 44, and after passing under two idlers 49', 50', that are arranged near the lower edge of the tracker box, extends rearwardly into the instrument, and passes around a sprocket wheel, (not shown) that receives motion from the motor mechanism of the instrument. No description of the motor mechanism of the instrument need be herein given, as such mechanism is well known, and forms no part of my present invention.

25 30 The clutch shaft 34 extends through the partition 26 and its outer end is journaled in a bearing 49' carried by the head 25, and upon the shaft 34, is fixed a small sprocket wheel 50, that receives motion from the sprocket wheel 47 when the clutch member 46 is engaged by the clutch member 45 through the medium of a chain 51.

35 40 The clutch member, 45 that is carried by a small sprocket wheel 44, is formed with a groove 45' that is embraced by the bifurcated end of a lever 51' which is pivoted at 52 and which has a curved projecting end 53, that extends somewhat beyond the end of the tracker box, and is engaged by a lug 54, 45 that is carried by a pivoted lever 55, that is entitled the "tempo" lever, and by the movement of which the tempo of the composition being played is regulated, and which lever also serves as a means whereby the 50 movement of the paper roll and the take-up roll can be reversed so as to unwind the paper from the take-up roll and upon the paper roll when it is desired to return the paper to the paper roll after a composition has been 55 played on the instrument. A flat bar 56, extends outwardly from the end of the tracker box and the outer end of the lever 55, is bent upwardly and slightly over the bar 56 and terminates in a pointer 57, by 60 means of which pointer and certain musical terms which are printed, impressed, or otherwise produced upon the top of the bar 56, serve as an index to indicate the tempo of the composition being played, it being understood that the position of the finger rela-

tive to the particular word on the bar shows the position of the lever 55 that is required to secure the desired tempo.

Near the inner end of the bar 56 the word "re-wind" appears, this word indicating that 70 when the pointer 57 is opposite this point the paper will be rewound upon the paper roll and such rewinding is accomplished in the following manner. When it is desired to re-wind the paper on the paper roll 30, the lever 75 55 is moved toward the end of the tracker box until the pointer 57 is opposite the word "re-wind". This movement of the lever 55 will bring the lug 54 into contact with the 80 curved end 53, of the lever 51, and move this lever so as to cause the small sprocket wheel 44, and the clutch member 45, to be moved to the left, this movement bringing the clutch member 45 into engagement with the clutch member 46 carried by sprocket wheel 47. 85 As the small sprocket wheel 44 and the clutch member 45 are fixed on the shaft 43, the lateral movement of the sprocket wheel and clutch member above described will move the shaft 43 to the left, in the direction of its 90 length, and this movement will throw the small pinion 42 out of mesh with the gear wheel 41 on the end of the take-up or feed roll 35. When the small sprocket wheel 44 has been moved as described and the clutch 95 members 45 and 46 brought into mesh with one another, the sprocket wheel 47 will be caused to revolve in unison with the small sprocket wheel 44, and the sprocket wheel 50 will be revolved in the same direction as the 100 sprocket wheel 47 through the medium of the chain 51 and positive motion will be thus imparted from the motor mechanism through the chain 48 and the intermediate mechanism above described to the paper roll 30, and 105 the paper will, by this means, be rewound upon the paper roll, the take-up roll turning freely by reason of the disengagement of the pinion 42 and the gear wheel 41.

110 Upon the left hand end of the tracker box and attached to the bracket 14 at that end, there is a laterally extending arm 58 which constitutes a support for certain devices for governing and regulating the volume of tone and the sustaining of the tones of the instrument, these devices being called expression levers, the effect produced by their operation being that of securing the proper and desired expression in the composition being played. These expression levers are three in number, 115 one of them being connected to and operating the sustaining devices of the instrument being played, while the other two govern and regulate, respectively, the volume of tone of the bass and treble portions of the instrument. The first mentioned lever is designated 59, and is pivoted at 60 to the arm 58 and to the inner end of the lever is pivotally attached at 61 a rod 62, which is suitably connected to the operating devices consti- 125 130

tuting the sustaining mechanism of the instrument being mechanically operated. Adjacent to the lever 59, is located a lever 63 that is pivoted at 64 to the arm, 58 and that is pivotally attached at 65 to a rod, 66, that in turn is connected to the expression devices of the instrument. A third lever 67, is pivoted at 68 to the arm 58, and is pivotally connected at 69 to a rod 70, leading to the expression devices of the bass portion of the scale of the instrument being played, the rod 66 of the lever 63 leading to the expression devices of the treble portion of the scale of the instrument. The pivotal connections 61, 65 and 69 are in alignment with one another and are all in alignment with the pivot bolts 15, and the lever 55 is provided with a hinge 71, which is also in alignment with the pivot bolts 15, this arrangement of parts being designed for the purpose of allowing the four levers 55, 59, 63 and 67, to be turned down to a vertical position when the tracker box is swung down to its inactive position below the key-board of the instrument.

25 The particular mechanism by means of which the tempo and the expression of the instrument being played are regulated, forms no part of my present invention except insofar as the construction and location of the levers and rods above described and shown are involved, as the particular mechanisms by means of which the tempo and expression of the composition are governed and regulated, form the subjects matter of other applications for patents filed by me and of even date herewith.

The operation of the devices above described is as follows:—The tracker box being in its normal or elevated position, and motion being communicated to the chain 48 by the motor mechanism of the instrument, the take-up roll 35 will be revolved in the direction of the arrow A and will draw the perforated sheet of paper B over the tracker bar 23. The speed at which the paper is fed across the tracker bar is regulated by the movement of the lever 55 to one or the other of the points on the bar 56 which are indicated by the characters designating the tempo of the movement or time of the composition being played. During the playing of the composition the levers 59, 63 and 67 are manipulated either simultaneously or successively or in any desired order, so as to give the proper expression required by the particular composition being played. When the composition has been played to the end, or at any time when it may be desired to repeat the playing of the composition or any part thereof, the lever 55 is moved toward the end of the tracker box until the pointer 57 is opposite the word "re-wind." At this position of parts, as hereinbefore described, the take-up roll 35 is disengaged from the driving mechanism and the paper roll en-

gaged therewith, and the paper will therefore be wound up upon the paper roll by the continuous action of the motor mechanism of the instrument. It may be stated incidentally, that during the rewinding of the paper on the paper roll, the parts which produce the operation of the action of the instrument are put in passive condition by the movement of the lever 55, but as the devices for accomplishing this result form no part of my present invention, I will not attempt to herein describe the same.

At any time when it is desired to play upon the keyed instrument to which the tracker box is applied, and to dispense with the mechanical playing devices, the tracker box is swung in the arc of a circle below the key-board of the instrument to the position shown in Fig. 1, and in dotted lines in Fig. 5 of the drawings, this change of position in 85 the tracker box being effected simply by pressing downwardly on the same so as to cause the latch blocks 12 to be disengaged from the heads 11 of the springs 8, whereupon the tracker box will swing upon the pivot 90 bolts 15 to assume the position shown in the above named figures of the drawings. When the tracker box has reached the proper position it is held by means of a spring catch 71 on one or both of the supporting bars, which 95 engages a pin 72, on bracket 14. A reverse movement of the tracker box will bring it again to the position shown in Fig. 2, and Fig. 5, the latch blocks 12 again engaging the heads 11 of the springs 8 as the tracker box 100 is moved upwardly.

While the arrangement of the paper roll and the take-up roll relatively to one another and the tracker bar which I have shown in the drawings and herein described is that which I prefer, it will be obvious to those skilled in the art to which my invention pertains, that the relative arrangement of these parts, as well as of the arrangement of the mechanism by which the paper roll and the 110 take-up roll are driven, may be altered without in any way departing from the spirit of my invention.

In Fig. 8 of the drawing I have shown in a modified form the means by which the tracker box is attached to the musical instrument, the purpose of the construction shown in this figure being to permit of the tracker box being not only hinged so as to be swung around under the key-board, as hereinbefore described, but also to permit of its being swung down and then detached from its pivotal support and entirely removed from connection with the instrument. This is accomplished by providing each of the 125 brackets with a hook 15' by means of which it is hooked onto the screw that forms the pivotal connection. By reason of this construction the tracker box may, if desired, be swung downwardly and then unhooked from 130

its pivotal supports and entirely removed, the drive chain and other connected parts being, of course, detached when the tracker box is removed in this manner.

5 Having described my invention, I claim:—

1. In apparatus of the character described, the combination of a suitable support arranged beneath the keyboard of an instrument and spring latches carried by said support, of a tracker box having a bracket located adjacent each end, said brackets being pivotally attached to said support at a point within the outer edge of the keyboard, latch blocks carried by said brackets and adapted 10 to engage said spring latches, an arm extending from one end of the tracker box, a tempo lever arranged adjacent to said arm and hinged in alinement with the pivotal supports of the said brackets, an arm extending 15 from the other end of the tracker box, a plurality of levers pivotally attached to said last named arm, and a rod pivotally attached to each of said last named levers, said last named rods being adapted to be connected 20 to the expression producing mechanism of mechanical musical instrument operating devices.

2. In an apparatus of the character described, the combination of a suitable support adapted to be secured in position beneath the keyboard of a keyed instrument, a jointing bar carried by said support, ducts leading from said jointing bar, a tracker box pivotally attached to said support, a movable 30 jointing bar carried by said tracker box, ducts leading from said movable jointing bar to said tracker box, means for sustaining said tracker box in such position relatively to said support that said jointing bars will be in contact with one another.

3. In an apparatus of the character described, the combination of a jointing bar, means for supporting said jointing bar, ducts leading from said jointing bar, a tracker box 40 pivotally supported on said means, a jointing bar carried by the tracker box, ducts leading from said last named jointing bar to said tracker box, and means for sustaining said tracker box in such position that the said 45 jointing bars will be in contact with one another.

4. In an apparatus of the character described, the combination with a suitable support and ducts attached to the support, of a movable tracker box connected to said support and ducts carried by the tracker box and adapted at one position of the tracker box to register with the ducts which are attached to the support. 55

5. In an apparatus of the character described, the combination with a suitable support adapted to be attached to a musical instrument, a cross-bar carried by said support, ducts leading into said cross-bar, of a removable tracker box pivotally connected 60 to said support, a cross bar carried by the tracker box, ducts leading from said cross-bar to said tracker box and adapted at one position of the tracker box to register with the ducts which are attached to the support. 70

6. In apparatus of the character described, the combination with a suitable support, adapted to be attached to a musical instrument, a tracker box detachably connected to said support and movable relative thereto 75 and means carried by the support and the tracker box for sustaining the tracker box in different positions while connected to the support, ducts carried by the tracker box and ducts carried by the support and adapted to register with the ducts carried by the tracker box at one position of the latter. 80

7. In an apparatus of the character described, the combination with a musical instrument and a suitable support arranged 85 below the key-board, of the musical instrument, of a playing attachment arranged within the case of said instrument, and a tracker box pivotally connected to said support, levers carried by said tracker box, rods 90 pivotally connected to said levers and connected to the playing attachment said levers and said rods having their pivotal connection in alinement with the pivotal connection of the tracker box with the support. 95

In testimony whereof I affix my signature in the presence of two witnesses.

WILLIAM F. COOPER.
